UNITED STATES PATENT OFFICE.

FERDINAND F. WAECHTER, OF PHILADELPHIA, PENNSYLVANIA, ASSIGNOR TO LINK-BELT COMPANY, OF CHICAGO, ILLINOIS, AND PHILADELPHIA, PENNSYLVANIA, A CORPORATION OF ILLINOIS.

BELT-CONVEYER IDLER.

No. 857,370.

Specification of Letters Patent.

Patented June 18, 1907.

Application filed November 3, 1906. Serial No. 341,904.

To all whom it may concern:

Be it known that I, FERDINAND F. WAECHTER, a citizen of the United States, residing in Philadelphia, Pennsylvania, have invented 5 certain improvements in Belt-Conveyer Idlers, of which the following is a specification.

The object of my invention is to make a light and substantial idler for the belts of 10 belt conveying apparatus.

Heretofore these idlers were usually cast and consequently were heavy and had to be bored and secured to the shaft by set screws or other fastenings. Furthermore it is very 15 difficult to properly balance a cast metal idler and I have found that in some instances, where the idler is not balanced properly, it will cause a drag on the belt which is objectionable on account of the wear.

20 By my invention I make an idler which can be readily balanced and which can be assembled without the use of separate fastenings if desired, and by means of disks which not only center the idler but also firmly secure it to the shaft.

25 In the accompanying drawing:—Figure 1, is a longitudinal sectional view of the preferred form of my improved idler; Fig. 2, is a perspective view of one of the pressed steel 30 bell ends; Fig. 3, is a perspective view of the disks; Figs. 4, 5, 6 and 7, are views illustrating modifications of my invention.

A is the shaft of any suitable length, which is usually mounted in bearings secured to the 35 frame of the structure on which the conveying mechanism is mounted.

B is the idler which is secured to the shaft so as to turn with it, this idler supports the conveying belt which may be of leather, fabric or any suitable material. Idler pulleys are placed a given distance apart in a belt conveying apparatus, so as to properly support the belt and its load and the idlers are usually enlarged at the end so that the sides 45 of the belt will be higher than the center. By this construction a greater amount of material can be conveyed by the belt.

50 My improved idler, as illustrated in Fig. 1, is made in three parts, a central tubular section C of the diameter desired, and two bell shaped sections D, D. The bell shaped sections are made by pressing a metallic plate (preferably steel), into shape, forming the flared body d and the head d'. The head

is reduced at d² so that the head portion will 55 extend into the tubular section C, the reduction is such that the outer surface of the bell section D will be on a line with the outer surface of the tubular section C, as indicated in Fig. 1.

60 The head d' of the section D is perforated for the passage of the shaft A, the opening being such as to allow the shaft to neatly fit the opening.

E, E are pressed metal disks, one at each 65 end of the idler, and these disks have an outer flange e of the same taper as the inner surface of the bell portions D, D and a hub flange e'.

70 The opening in the disks is a trifle less than the diameter of the shaft so that when the parts of the idler are assembled the disks must be forced onto the shaft with considerable pressure in order that the disks will be firmly fixed to the shaft and by forcing the 75 disks into the enlarged ends of the sections D, D the bevel flanges of the disks will be forced firmly against the inner surface of the bell ends, centering the bell sections and at the same time firmly attaching the assembled 80 parts to the shaft.

It will be understood that the central section C may be of any length desired and the sections D, D may also be of any length, depending considerably upon the character of 85 the pulley to be designed for a certain class of work.

In some instances I may make the pulley as shown in Fig. 4, in which the several sections C and D are dispensed with and a single tubular section B' used. This section is flared at each end so as to not only enlarge the idler at each end for the purpose of shaping the belt as it passes over the pulley, but also to provide a tapered surface for the 95 disks E' which are forced into each end of the section B'.

The bell ends D may, in some instances, be made very short as illustrated in Fig. 5, when it is desired to make an abrupt flange 100 at each end of the idler, as indicated at D', or the disks may be shaped to form part of the flange as indicated at E², Fig. 6.

In Fig. 7, I have shown the bell section D² made in two parts, d, d', the part d' being in 105 fact a flanged disk which is forced on the shaft and which supports the abutting edges of the sections d and C.

In some instances I may hold the disks in position after they are mounted on the shaft, by means of collars, set screws, or other devices, as an extra precaution, but I prefer to 5 use the construction illustrated in Fig. 1, not only on account of its strength but also that it is readily assembled and the parts can be perfectly balanced, and the interior of the drum will be closed against the entrance of 10 dirt and dust.

I claim:—

1. The combination of a shaft, a tubular body portion flared at each end, pressed metallic disks each having a flange flared on the 15 same line as the inside of the flare of the body portion and having a tubular hub confined to the shaft, substantially as described.

2. The combination in an idler, of a shaft, a central tubular section, end sections fitting 20 in the tubular section, and disks mounted on the shaft and forced into the flared ends of the pressed end sections, substantially as described.

3. The combination in an idler, of a shaft, 25 a central tubular section, pressed metallic end sections fitting in the tubular section, and disks mounted on the shaft and forced into the flared ends of the pressed end sections, substantially as described.

30 4. The combination of a shaft, a tubular central section, two pressed end sections

flared and having reduced portions at their inner ends, said reduced portions fitting in the ends of the central section, with disks mounted on the shaft and extending into the 35 flared portions of the end sections, substantially as described.

5. The combination of a shaft, a tubular central section, two pressed metallic end sections flared and having perforated heads 40 through which the shaft passes, and flanged disks mounted on the shaft, the flanges of the disks fitting within the flared portions of the end sections, substantially as described.

6. The combination of a shaft, a tubular 45 central section, pressed metallic bell shaped end sections having perforated heads, the shaft passing through the perforations in the heads, a pressed metallic disk having a flange shaped to conform with the flare of the bell 50 shaped end sections and having a hub flange forced onto the shaft, the disks retaining the several parts in position and securing them rigidly to the shaft, substantially as described.

55 In testimony whereof, I have signed my name to this specification, in the presence of two subscribing witnesses.

FERDINAND F. WAECHTER.
